Patented Nov. 4, 1975

237,540

COMBINED SCREENING, CONVEYING, WASHING, SEPARATING AND DE-WATERING APPARATUS FOR QUARRYING

Patrick O'Neill, Glenmount Park, and Patrick Joseph
Douglas, Annvale, Killyman Road, both of Dungannon,
County Tyrone, Northern Ireland

Filed Feb. 19, 1974, Ser. No. 443,611

Claims priority, application Great Britain Aug. 18, 1973

Term of patent 14 years

Int. Cl. D12—05; D15—99

U.S. Cl. D55—1 C

FIG. 3.

FIG. 1 is a side elevational view of a combined screening, conveying, washing, separating and de-watering apparatus for quarrying, showing our invention, the side opposite that shown in FIG. 1 being a substantial mirror image of the side shown in FIG. 1;

FIG. 2 is an end elevational view from the right side of FIG. 1; and

FIG. 3 is a top plan view thereof.

We claim:

The ornamental design for a combined screening, conveying, washing, separating and de-watering apparatus for quarrying, as shown and described.
